CLAIM

The ornamental design for a water bottle, as shown and described.

DESCRIPTION

FIG. 1 is a top, front, right side perspective view of a water bottle showing my new design;

FIG. 2 is a bottom, rear, left side perspective view thereof;

FIG. 3 is a front elevation view thereof;

FIG. 4 is a rear elevation view thereof;

FIG. 5 is a left side elevation view thereof, the right side elevation view being a mirror image of the left side elevation view;

FIG. 6 is an enlarged top plan view thereof;

FIG. 7 is an enlarged bottom plan view thereof;

FIG. 8 is a top, front, right side perspective view thereof shown separated for clarity of disclosure; and,

FIG. 9 is a bottom, rear, left side perspective view of the water bottle with the bottle lid being detached.

The broken lines in the drawings illustrate portions of the water bottle that form no part of the claimed design.
